UNITED STATES PATENT OFFICE.

LOUIS M. BUTTERFIELD, OF RAYMOND, NEW HAMPSHIRE, ASSIGNOR, BY MESNE ASSIGNMENTS, TO MCVETY TOY COMPANY, OF CORINNA, MAINE, A CORPORATION OF MAINE.

ANIMATED TOY.

Application filed March 16, 1926. Serial No. 95,102.

This invention relates to a figure toy of the animated type, and has for one of its objects the provision of a novel, simple and inexpensive device of this character which 5 can be made in imitation of any quadruped and which shall embody means adapted to impart a lifelike walking or running movement to the toy.

With the foregoing and other objects in view, the invention consists of the novel construction, combination and arrangement of parts hereinafter fully described and claimed, and illustrated in the accompanying drawings, wherein:

15 Figure 1 is a view partly in elevation and partly in vertical section of an animated toy constructed in accordance with my invention.

20 Figure 2 is a sectional view taken on the vertical plane extending longitudinally and centrally through the body of the toy,

25 Figure 3 is a sectional view taken on the horizontal plane indicated by the line 3—3 of Figure 2;

Figure 4 is a similar view taken on the vertical planes indicated by the line 4—4 of Figure 2;

Figure 5 is a detail sectional view taken on the vertical plane indicated by the line 5—5 of Figure 4, and

Figure 6 is a similar view taken on the vertical plane indicated by the line 6—6 of Figure 3.

Corresponding and like parts are referred 35 to in the following description, and designated in the several views of the accompanying drawings, by similar reference characters.

The toy comprises a body A, head B, fore 40 legs C and hind legs D. The body A is hollow and preferably made of light sheet metal, and consists of a top side 1, lateral sides 2 and rear side 3. The front ends 45 of the lateral sides 2 are of substantially V-form, and are connected by an upwardly and rearwardly inclined cross piece 4. Vertically disposed and relatively spaced plates 5 are located within and extend longitudinally of the body A. The plates 5 are provided at their bottom edges with outwardly directed flanges 5^a which are provided at their outer edges with tongues 5^b passing through openings 2^a in the lateral

sides 2 of the body A and contacting with the outer surfaces of the sides. The tongues 5^b secure the plates 5 to the body A, and the sides 1, 2 and 3 of the body are formed integrally. The rear side 3 of the body A is secured to the rear edges of its lateral sides 2 in any suitable manner. The cross piece 4 is preferably formed integrally with one of the lateral sides 2 of the body A and is secured to the other of said sides in any suitable manner. The plates 5 are connected together and maintained in relatively spaced relation by rods 6, 7, 8 and 9, and are provided at their top edges with upwardly and outwardly extending front lugs 10 and similar rear lugs 11.

The fore legs C and hind legs D are hollow and preferably made of light sheet metal. The fore legs C are secured as at 12 to front levers 13, and the hind legs D are secured as at 14 to rear levers 15. The levers 13 and 15 are similar and have their upper ends pivoted as at 16 to the lugs 10 and 11. The pivot shafts 16 are journaled in the lugs 10 and 11 and pass through the looped upper ends 17 of the levers 13 and 15, said ends of the levers embracing the lugs 10 and 11. The levers 13 and 15 pass through openings 18 in the flanges 5^a, and are provided at their lower ends with rollers 19. Tires 20 of rubber or any other material possessing good tractive qualities are mounted on the rollers 19. Metal strips 21 having their lower end portions spaced from the corresponding portions of the levers 13 and 15, are secured to the levers by rivets 22 and tie and spacing strips 23. Shafts 24 upon which the rollers 19 are journaled, are carried by the lower ends of the levers 13 and 15 and straps 21. Ratchet wheels 25 fixed to the rollers 19, and pawls 26 pivoted to the levers 13 and 15 are held by gravity in engagement with the ratchet wheels, permit the rollers to turn during the forward movement of the levers 13 and 15 and hold the rollers against movement during their return or rearward movement, with the result that the toy will have imparted thereto a forward movement. The legs C and D move with the levers 13 and 15, and due thereto a lifelike walking or running movement is imparted to the toy. The levers 13 and 15 are adapted to be operated

through the medium of a shaft 27 provided at its ends with cranks 28 which have an opposite diametric arrangement. The shaft 27 is journaled in the plates 5, and the cranks 28 thereof pass through vertical slots 29 in the levers 13. Rollers 30 are journaled on the cranks 28 and extend through the slots 29 in contact with the side walls thereof. The pair of levers 13 and 15 at each side of the body A are connected for simultaneous forward and backward movement by a link 31 which is pivoted to the levers as at 32.

A motor spring 33 connected at one end to and wound about a winding shaft 34, and connected at its other end to the rod 6, is adapted to drive the shaft 27 through gears 35, 36, 37 and 38. The gear 35 is loose on the shaft 34, and is connected thereto through the medium of a ratchet wheel 39 and detent 40. The gears 36 and 37 are fixed to a shaft 41 journaled in the plates 5, and the gear 38 is fixed to the shaft 27. A detent 42 of U-form is slidably mounted on the rod 7 for movement into and out of engagement with the gear 38. The detent 42 when in engagement with the gear 38, as shown by dotted lines in Figure 4, holds the crank shaft 27 against rotation by the motor spring 33, and when it is out of engagement with the gear, as shown by solid lines in said figure, the crank shaft is free for rotation by the motor spring. The detent 42 is supported on the rod 7 by a rod 43 which extends through the rear side 3 of the body A and through the medium of which the detent may be moved into and out of engagement with the gear 38. A key 34^a, through the medium of which the motor spring 33 may be wound up, is threadedly connected to the shaft 34.

The head B is carried by the body A and is mainly supported by the cross piece 4 of the body. It may be of any suitable construction, and as shown comprises an envelop 44 and a filling of any suitable material. The body A and the legs C and D are provided with covers 45 and 46, respectively, of any suitable material, and the former is also provided with a padding 47 of any suitable material.

In practice, after engaging the detent 42 with the gear 38, the motor spring 33 is wound up. The toy is then placed on the floor, table or the like, and thereafter the detent 42 is moved out of engagement with the gear 38. As the lower side of the body A is open, the lower front end of the rod 43 may be readily grasped when it is desired to move the detent 42 into or out of engage-

ment with the gear 38. The upper rear end 60 of the rod 43 is provided with a head 48 which contacts with the outer surface of the rear side 3 of the body A and constitutes a fulcrum upon which the rod swings during its manipulation to move the detent 42 into 65 or out of engagement with the gear 38. The rotation of the crank shaft 27 by the motor spring 33 alternately swings the levers 13 and 15 and legs C and D at opposite sides of the body A in opposite directions. As 70 the rollers 19 are free to rotate forwardly and are held against rearward rotation by the detents 26, the swinging of the levers 13 and 15 and legs C and D will move the toy over the supporting surface in a lifelike 75 manner.

It should be understood that the drawings are merely illustrative and do not pretend to give exact proportions. Furthermore, the said drawings are illustrative of a preferred 80 construction, it being my expectation that various changes and modifications may be made without departing from the spirit and scope of my invention.

What is claimed is:—

1. A toy comprising a body, a pair of levers pivoted to each side of the body, a link connecting each pair of levers, a crank shaft connected to one lever of each pair, a motor for operating the crank shaft and 90 including a gear fixed to the crank shaft, a rod carried by the body, a U-shaped detent slidably mounted on the rod for movement into and out of engagement with the gear, and a rod passing through the detent to retain it on the first named rod and providing means by which the detent may be moved into and out of engagement with the gear. 95

2. A toy comprising a body, plates vertically arranged within the body in relatively 100 spaced relation and in spaced relation to the sides of the body, said plates being provided at their lower edges with outwardly directed flanges secured to the sides of the body, said plates being provided at their upper edges with upwardly and outwardly extending lugs and said flanges being provided with 105 openings, shafts carried by the lugs, a pair of levers positioned between each plate and each side of the body and passing through the openings in the flanges, said levers being provided with angular upper ends engaging the shaft at opposite sides of the lugs, a link connecting the levers of each pair, and lever operating means carried by the plates. 110

In testimony whereof I affix my signature.

LOUIS M. BUTTERFIELD.
